WELL FLOWING APPARATUS

Thomas E. Bryan, Oklahoma City, Okla.

Application April 20, 1936, Serial No. 75,265

6 Claims. (Cl. 103—232)

This invention relates to valves for use in oil wells or the like, adapted to control the admission of gas or air into a column of fluid within the well so as to aerate the fluid and cause it to rise due to its decreased density.

It has been the practice in recent times to force gas or air under pressure into a column of oil or other fluid within a well so as to aerate the fluid and make it possible for the natural pressure existing at the bottom of the well to force the lightened fluid from the top of the well. The admission of this gas or air has been effected in the past by providing the well with an outer casing and an inner tubing, flowing the well through the tubing or through the space between the tubing and the casing, and forcing into the well through the space that is not being used for flowing the well a supply of gas or air under pressure. Valve means have been provided at various intervals in the wall of the tubing so as to admit the gas or air from the tubing into the casing or vice versa. These have for the most part been controlled by the relative pressures of the column of fluid standing in the well and the pressure of the gas injected into the well.

More recently, certain types of valves have been developed for controlling the admission of gas or air into a column of fluid, which valves are controlled by the velocity or by the flow of fluid in an upward direction. In this type of valve, the valve is normally opened to permit gas to pass into the fluid column when the fluid is not in motion. However, as soon as the fluid begins to flow, the velocity of the fluid is utilized to cause a closing of the valve and thus to prevent the admission of any more gas or air into the fluid column until the flow stops.

It is an object of this invention to provide a valve of the latter type which is of greatly simplified construction, as compared with valves of the same general type heretofore used.

It is a further object of this invention to provide a valve which will be positive in its operation and which will be of such construction that it will be impossible for it to become jammed or stuck and continue to admit gas or air into the fluid column after the fluid column has begun to flow.

Another object of this invention is to provide a device which will perform the functions stated and will, in addition, serve as a check valve to prevent downward flow of the column of fluid.

One other object of this invention is to provide such a structure with a check valve which will

automatically seat in its proper position at all times that there is no fluid flow.

With the above and other objects in view, this invention contemplates a structure including the various parts and combinations illustrated in the accompanying drawings and set forth in the following description, it being understood, however, that the accompanying drawings and the following description are by way of illustration and example only and are not to be taken as in any way limiting the object or scope of this invention. Such limitation is to be only by the prior art and by the terms of the appended claims.

Referring now more particularly to the drawings in which like numerals indicate corresponding parts throughout:

Fig. 1 is a view in vertical cross section illustrating the application of valves constructed in accordance with this invention to an oil well or the like.

Fig. 2 is a horizontal cross section through a section of tubing having one of these valves installed therein, this section being taken along the line 2—2 of Fig. 3.

Fig. 3 is an enlarged view similar to a portion of Fig. 1 but illustrating one of the valves partly in section.

Fig. 4 is a greatly enlarged view illustrating the details of construction and operation of one of these valves.

Fig. 5 is a view similar to Fig. 2 but illustrating a slightly modified form of construction and represents a section taken along the line 5—5 of Fig. 6.

Fig. 6 is a view similar to Fig. 3 but illustrating the modification shown in Fig. 5 with the valve in position to admit gas into the fluid column.

Fig. 7 is a view similar to Fig. 6 but showing the valve in the position it occupies when the fluid column within the well is in motion.

Referring now more in detail to the form illustrated in Figs. 1 to 4, inclusive, Fig. 1 illustrates the application of the valve in which a casing 1 is lowered into the well hole through the formation 2, and the tubing 3 is then placed within the casing 1. At spaced intervals, usually in the neighborhood of 200 feet or so, there is inserted into this tubing a section having a partition 4 secured therein in a transverse position by any suitable means such as by welding 5. This partition is provided with an opening 6 therethrough having a tapered substantially conical valve seat 7 adjacent the upper face of the partition.

At a point just above the partition and spaced laterally with respect to the opening 6 is a hollow

shaft 8 extending transversely of the tubing and through the tubing walls at its opposite ends. This shaft is secured in position by means such as welding 9. At spaced points on this shaft are 5 provided a pair of thrust collars 10 and 11, between which is positioned a valve sleeve 12 surrounding the shaft 8 and having a laterally extending arm 13 integral therewith. Secured to the underside of the arm 13 in such a position 10 as to seat against the valve seat 7 and close the opening 6 is a valve 14 having a tapered substantially conical seat portion 15.

The shaft 8 which communicates at its opposite end with the exterior of the tubing 3 is formed 15 with an opening 16 in its upper side at a point intermediate the thrust collars 10 and 11. Formed in the sleeve 12 is a corresponding opening 17 adapted to register with the opening 16 when the valve member 14 is seated against the 20 seat 7. This opening 17 is slightly elongated so as to register at all times regardless of any slight end-wise movement of the sleeve 12. In order to insure against the valve member 14 being swung upwardly to such a point that it would rest 25 against the wall of the tubing 3 and not fall back into its seated position, there may be provided any suitable stop or other means such as the pin 18 which is shown as being positioned on top of the arm 13. This pin as illustrated will stop 30 the swinging movement of the valve 14 in such a position that the force of gravity will tend to pull the valve back into its closed position.

In Figs. 5, 6 and 7 there is illustrated a slightly modified form of construction. In this instance, 35 the partition 4 is replaced with a similar partition 19 which does not, however, include the substantially conical valve seat at the upper end of its opening 21. The opening 21 may be cylindrical or any other suitable shape throughout.

40 In this form also the sleeve 12 and arm 13 have been replaced by an arm 22 which is bifurcated at its end opposite the hollow shaft 8 to provide spaced ears 23 and 24 between which are positioned a lug 25 carried by a substantially hemispherical valve member 26. This lug 25 is pivotally secured in place by means of a pin 27 passing through the ears 23 and 24. Because of its hemispherical formation, the valve 26 will seat against and close the opening 21, adjusting 45 itself automatically to any minor irregularities in the positioning of the opening 21, or in the swinging of the arm 22. A stop 28 or similar means may be provided so that when the valve is forced upwardly by a flow of fluid as hereinbefore described, it will not be swung entirely over to a position which will prevent it from seating when it is moved downwardly again. The arm 22 is provided with an opening 29 similar to the opening 17 in the sleeve 12 and for the same 50 purpose.

55 In operation, a plurality of valves are positioned in a well in spaced relation as above set forth. The tubing 3 is adapted to provide a passage through its interior 30 for the flow of fluid from the well. The space 31 between the tubing and the casing 1 is adapted to receive air or gas under pressure. So long as the pressure of the formation which is producing the fluid is sufficient to cause it to flow through the tubing 70 3 to the surface of the ground without any outside assistance, the valves 14 or 26, as the case may be, will be held open. Under these circumstances, the openings 16 and 17 in the one form, and 16 and 29 in the other form, will be out of register so that there will be no flow of gas from 75

the space 31 through the hollow shaft 8 and into the tubing 3.

When the pressure in the formation falls to a point where it is insufficient to raise the column of fluid within the space 30, the valves 14 or 26 5 will be moved by gravity, or by a slight downward motion of the fluid into seating engagement with the openings formed through the partitions 4 or 19. These valves thus serve as check valves to prevent downward motion of the fluid within the 10 tubing. When the valves 14 or 26 are in closed position, however, the openings 16 and 17, or 16 and 29, will come into register. It will then be possible for the air or gas under pressure within the space 31 to flow inwardly through the hollow 15 shaft 8 and through the openings 16 and 17 or 16 and 29 into the space 30 within the tubing. The gas thus entering the tubing will be dispersed into the fluid standing in the tubing, and will serve to lighten this fluid because of its introduction to such an extent that the pressure within the well formation will be sufficient to lift the fluid column in its lightened condition. The well will then begin to flow again, and the valve 14 or 26 will be opened to shut off the flow of gas 20 until the well stops flowing.

It will be noted that in using a plurality of these valves within a well, the static pressure of the column of fluid within the space 30 is less at the position of the uppermost valve and gradually increases until it is greatest at the position of the lowermost valve. This being the case, the gas will first be introduced into the tubing through the uppermost valve, and if this is insufficient to start the flow of fluid, the gas will be 35 introduced at the next lowest valve, and so on down to the position of the lowest valve. Thus, it is possible to aerate the entire column of fluid above the lowest valve when this becomes necessary to lighten the column sufficiently so that the 40 pressure in the well formation will cause it to rise.

From the foregoing it will be appreciated that there has been provided by this invention an extremely simple form of valve for getting air or gas pressure into a tubing to cause the flow of a column of fluid therein. It will also be appreciated that the valve thus provided is governed entirely by the flow of the fluid as distinguished from the pressure of the fluid within the tubing space 30. In addition to its function as a valve 45 for admitting or excluding air or gas under pressure to or from the tubing, the invention set forth provides at each position of such a valve a check valve for preventing the downward flow of the column of fluid within the well. This check valve is in each case positive in its action and capable of performing all of the functions 50 ordinarily performed by a check valve.

Having described my invention, I claim:

1. In combination with a well tubing having an 6 opening through a wall thereof to admit gas under pressure thereto, a rotatable sleeve valve for controlling said opening, and means connected to said sleeve valve and located in the path of a fluid passing through said tubing for rotating 6 said valve to close said opening upon upward movement of such fluid and for rotating said valve to open the same upon cessation of such upward movement.

2. In combination with a well tubing, a partition 7 extending transversely of said tubing and having an opening therethrough, a hollow shaft extending transversely of said tubing above said partition and having its interior in communication with the exterior of said tubing, an arm 7

5 rotatably mounted on said shaft, and valve means on said arm adapted to close said opening in said partition and movable away from said opening upon upward motion of a fluid through said tubing, said hollow shaft having a lateral opening therein, and said arm having a part thereon movable to close said lateral opening when said valve means is moved away from the opening in said partition.

10 3. In combination with a well tubing, a partition extending transversely of said tubing and having an opening therethrough, a hollow shaft extending transversely of said tubing above said partition and having its interior in communication with the exterior of said tubing, a sleeve rotatably mounted on said shaft and having a laterally extending arm thereon, and a valve member on said arm swingable about said hollow shaft to close or open the passage through said 15 partition, said hollow shaft and sleeve having openings therein adapted to register when said valve member is in position to close said passage through the partition and adapted to move out of register when said valve member is moved to open said passage.

20 4. In combination with a well tubing, means therein providing a substantially conical valve seat, a hollow shaft above said means having its interior in communication with the exterior of said tubing, an arm rotatably mounted on said shaft, a valve member rigidly mounted on said arm and having a substantially conical seating portion adapted to cooperate with said valve seat to close said tubing and movable from said seat 25

on upward movement of a fluid in said tubing, said hollow shaft having a lateral port therein, and means on said arm adapted to close said port upon movement of said valve member from said valve seat.

5 5. In combination with a well tubing, means therein providing a restriction presenting an upwardly facing shoulder, a hollow shaft above said means having its interior in communication with the exterior of said tubing, an arm rotatably mounted on said shaft, a valve member pivotally mounted on said arm and having a portion adapted to cooperate with said shoulder to close said tubing and movable from said shoulder on upward movement of a fluid in said tubing, 10 said hollow shaft having a lateral port therein, and means on said arm adapted to close said port upon movement of said valve member from said shoulder.

15 6. In combination with a well tubing, means 20 therein providing a restriction presenting an upwardly facing shoulder, a hollow shaft above said means having its interior in communication with the exterior of said tubing, an arm rotatably mounted on said shaft, a valve member 25 pivotally mounted on said arm and having a hemispherical portion adapted to cooperate with said shoulder to close said tubing and movable from said shoulder on upward movement of a fluid in said tubing, said hollow shaft having 30 a lateral port therein, and means on said arm adapted to close said port upon movement of said valve member from said shoulder.

THOMAS E. BRYAN.
